(57) **CLAIM**

The ornamental design of a board for simulating water sports, as shown and described.

DESCRIPTION

FIG. 1 is a top view of the board for simulating water sports according to a first embodiment of the present invention showing a first position for the feet;

FIG. 2 is a top view of the board for simulating water sports according to a second embodiment of the present invention showing a second position for the feet;

FIG. 3 is a top view of the board for simulating water sports according to a third embodiment of the present invention showing a third position for the feet;

FIG. 4 is a side view of the board for simulating water sports for all three embodiments;

FIG. 5 is an end view of the board for simulating water sports for all three embodiments;

FIG. 6 is a perspective front view of the second embodiment;

FIG. 7 is a perspective front view of the first embodiment;

FIG. 8 is perspective front view of the third embodiment; and,

FIG. 9 is a bottom view of the board for simulating water sports of FIGS. 1-8.
